United States Patent Office

Des. 175,625

Patented Sept. 20, 1955

175,625

COMBINATION AIR CONDITIONER, HEATER, AND BEVERAGE COOLER OR THE LIKE

William E. Lind, Fort Worth, Tex., assignor to A. R. A.
Manufacturing Company, Fort Worth, Tex., a corpo-
ration of Texas

Application November 1, 1954, Serial No. 32,882

Term of patent 14 years

(Cl. D62—4)

FIG. 1.

FIG. 2.

FIG. 3.

FIG. 4.

Fig. 1 is a front view of the combination air conditioner, heater and beverage cooler or the like, showing my new design with the door for the beverage cooler compartment open;

Fig. 2 is a front view as in Fig. 1 but with the door closed;

Fig. 3 is a top view;

Fig. 4 is a left end view.

The back and end not shown in the drawings are plain.

I claim:

The ornamental design for a combination air conditioner, heater, and beverage cooler or the like, as shown and described.
